US0D1004791S

(12) **United States Design Patent** (10) **Patent No.:** **US D1,004,791 S**
(45) **Date of Patent:** **** Nov. 14, 2023**

(54) **MASK**

(71) Applicant: **Therabody, Inc.**, Los Angeles, CA (US)

(72) Inventors: **Benjamin Nazarian**, Beverly Hills, CA (US); **Jaime Sanchez Solana**, Los Angeles, CA (US); **Eduardo Merino**, Los Angeles, CA (US); **Mandar Deshmukh**, Los Angeles, CA (US); **Kevin Xie**, Los Angeles, CA (US); **William Webb**, San Francisco, CA (US)

(73) Assignee: **Therabody, Inc.**, Los Angeles, CA (US)

(**) Term: **15 Years**

(21) Appl. No.: **29/875,687**

(22) Filed: **May 9, 2023**

Related U.S. Application Data

(63) Continuation of application No. 29/868,829, filed on Dec. 14, 2022.

CLAIM

The ornamental design for a mask, as shown and described.

DESCRIPTION

FIG. 1 is a top front isometric view of a mask showing the claimed design;

FIG. 2 is a top rear elevation view thereof;

FIG. 3 is a bottom rear isometric view thereof;

FIG. 4 is a front elevation view thereof;

FIG. 5 is a rear view thereof;

FIG. 6 is a right side elevation view thereof;

FIG. 7 is a left side elevation view thereof;

FIG. 8 is a top plan view thereof; and,

FIG. 9 is a bottom plan view thereof.

The broken lines in the figures show portions of the mask that form no part of the claimed design.
